UNITED STATES PATENT OFFICE.

GEORGE W. RUTHVEN, OF DONNA, TEXAS.

CHAIN-TIGHTENING TOOL.

1,276,815.

Specification of Letters Patent. Patented Aug. 27, 1918.

Application filed June 23, 1915. Serial No. 35,916.

To all whom it may concern:

Be it known that I, GEORGE W. RUTHVEN, a citizen of the United States, residing at Donna, in the county of Hidalgo and State 5 of Texas, have invented certain new and useful Improvements in Chain-Tightening Tools, of which the following is a specification.

My present invention relates to an improved tool to tighten chains on automobile wheels, etc.

The main object of the device is to provide a thoroughly efficient tool of this character which is simple in construction and 15 may be manufactured at a comparatively low cost.

In carrying into effect this main object I have provided a tool of the above nature which will automatically lock when the required adjustment is attained in order that 20 both hands of the operator will be free to manipulate the chain fastening device. Various other objects and advantages will become apparent during the continuance of 25 the following description.

The above and other objects which will become apparent are accomplished by such means as shown in their preferred form in the accompanying drawings, described in 30 the following specification and then more specifically pointed out in the appended claim.

In the accompanying drawings wherein like character designate like parts throughout the several views;

Figure 1 is a perspective view of my invention.

Fig. 2 is a sectional view taken on line 2—2 of Fig. 1 in the direction indicated by 40 the arrow.

My invention consists generally of a pair of substantially complementary levers which include body portions 10 and 11, provided at one end with handles 12 and 13 while 45 their other ends are curved to form oppositely extending arms 14 and 15. Adjacent their respective outer extremities, the arms 14 and 15 are cut away to provide suitable gripping lips or hooks 16 and 17 which in the use of my invention serve to 50 engage the respective portions of the tire chain. In assembling the levers, the arms 14 and 15 respectively are pivotally connected through the medium of a rivet 18 at a point appreciably below the point of bending 55 of the arms from the bodies 10 and 11,

thus by reason of the proportion of length of the respective bodies, a greater leverage may be obtained when manipulating the device.

60

In consistence with the foregoing I have provided means for locking the respective levers in a rigid position after the tire chain has been tightened to a desired degree, in order that the operator may have the use 65 of both hands when adjusting the chain fastener. To this end, the body 11 is provided with a suitably curved segmental rack 19 which is secured thereto through the medium of the rivets 20. The teeth 21 on the 70 rack are preferably on the upper edge thereof in order that they may be positively engaged by a pivoted dog 24 on the other body 10. For the purpose of guiding the segmental rack during the movement 75 of the respective bodies, the body 10 is provided with a guiding bracket 22 which is rigid thereon as at 23 and engages the rack in the manner clearly illustrated.

A dog 24 is pivoted to the body 10 at a 80 point 25 which is in proximity to the rack 19 and carries an enlarged portion 26 for the purpose of receiving one end of a rod 27. The other end of the rod 27 has connection with an intermediate portion of a bell crank, 85 operating lever 28 which is in turn pivotally connected to the body 10 as at 29. It will now be recognized that the bodies may move toward each other to tighten the 90 respective chain sections 30 and 31 to a desired degree. However at the termination of such adjustment the dog 24 will engage the abrupt face of the adjacent one of the teeth 21 in the manner which will prevent the reverse movement of the rack 19. When 95 this operation occurs, the respective jaws are retained in a fixed position relative to one another while the operator may release the handle portions 12 and 13 and direct his efforts to securing the chain sections together through the medium of the chain fastener (not shown).

From the foregoing it is believed that the construction of my invention will be readily understood, as will the advantages and 105 novel features of the device. However, it will be recognized that the device is not limited to use in combination with tire chains as the same may be advantageously employed for other purposes if it is so desired.

In reducing my invention to practice I

find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without 10 sacrificing any of the advantages of my invention as defined in the appended claim.

Having thus fully described my invention, what I claim as new and desire to secure by Letters Patent is:

15. A tire chain tightening tool, comprising like members, each having a handle at one end and a curved arm at the opposite end terminating in a hook, said members having their curved arms crossing and pivoted

at the point of crossing, a segmental rack 20 secured rigidly to one member, a guide secured to the other member and embracing the segmental rack, the end of the guide facing the toothed edge of the rack being open, a dog pivoted to the member provided with the guide and disposed opposite the open end of said guide to engage the toothed edge of the rack, and manually operable means mounted on the member carrying the dog and guide adjacent the 25 handle of said member and connected with the dog for operation thereof.

In testimony whereof I affix my signature in presence of two witnesses.

GEORGE W. RUTHVEN.
